PROCESS OF MAKING FERRO-ALLOYS

Lawrence G. Pritz, North Canton, Ohio, assignor
to Ohio Ferro-Alloys Corporation, Canton,
Ohio, a corporation of Ohio

Application November 25, 1944, Serial No. 565,111

2 Claims. (Cl. 75—11)

1

This invention relates to a process of making ferro-alloys. It is herein particularly described as applied to the making of ferro-silicon.

Ferro-alloys have heretofore been commonly made in three ways: (a) in the blast furnace, (b) by the thermit process, and (c) in the electric furnace, but the limitations of the two processes first mentioned are such that the electric furnace process predominates. Nevertheless, the electric furnace process of making ferro-alloys as heretofore carried out has serious disadvantages and limitations. These have been due in considerable part to the requirements of practical production operation, rather than to theoretical process limitations, and are well known to operating men. The furnaces employed are of the open-top type. A charging floor is located at the top level of the furnace and the furnace has been manually charged. The electric current, generally three-phase, is supplied through electrodes suspended vertically from a structure above the furnace. The manufacture of ferro-alloys involves maintaining a very high temperature in the reaction zone, and since a considerable part of the furnace equipment, including the electrodes, holders, clamps and suspending chains or cables, is mounted vertically over the open-topped furnace, it is subject to intense heat.

In order to get any reasonable life out of the elements located over the furnace, they must be well protected and, insofar as is possible, water-cooled. The water-cooling system is very extensive and must be kept in first-class condition, frequently entailing the use of special water-treatment, e. g., special softening procedures. Even so, the life of many of the parts is quite limited, and the manufacturing cost is thereby burdened. This is especially so of the electrode clamps, which, for reasons of electrical efficiency, are located close to the top of the furnace charge.

It has been proposed to minimize the effect of the intense heat on the clamps by clamping the electrodes near their tops, but this proposal has been open to the objection that the electrical efficiency is thereby impaired, with resultant increase in manufacturing costs. Attempts have also been made to shield the equipment by means of refractory and water-cooled roofs, but such structures are costly to construct and difficult to maintain. For these reasons, among others, the various proposals for improvement, heretofore made, have not found acceptance.

Apart from deterioration by reason of the intense heat, the equipment above the furnace proper is subject to impairment by corrosion, dust

2

and "blows." In the manufacture of ferro-alloys, large quantities of hot gases are evolved. These gases pass upwardly and continuously entrain dust from the furnace charge. The gases constantly tend to channel locally through the charge, taking the paths of least resistance. They are evolved in such quantity that substantial pressures are generated, and it is a routine occurrence that "blows" result, wherein the gases open up large channels and rush out through the top of the charge at high velocity and in great local volume, instead of permeating the charge with reasonable uniformity and escaping at relatively low velocity over substantially the whole area of the furnace charge. Blows are particularly prone to occur around the electrodes. Since the electrodes extend upwardly from the furnace chamber, the charge cannot extend uninterruptedly over the area of the furnace chamber, and there is inherently less resistance to the flow of gases where the granular charge is in contact with the generally smooth and unbroken electrode surfaces than in those portions where the gases must find their way through serpentine paths afforded by more or less interfitting charge material. Moreover, the surface of the charge material is not static around the electrodes, but is constantly feeding downwardly, so that the tendency to "blow" around the electrodes is enhanced.

It is customary under very severe heat, etc., to provide metal cases for the projecting parts of the electrodes so they will not deteriorate.

Furnaces for the manufacture of ferro-alloys are manually charged because, by reason of the factors just stated, the workmen must closely watch the working of the furnace and distribute the charge over the furnace as conditions may dictate. Even so, the presence of the projecting electrodes makes their task a difficult one, and great skill and endurance are required to place the charge material properly.

The physical requirements for operating a ferro-alloy furnace are such that only sturdy and/or youthful men can withstand it. The workmen are constantly subjected to adverse heat conditions, and these conditions are greatly aggravated when, as is frequently the case, they find it necessary to shovel or rake charge material into localized spots to prevent blows or check blows which have already begun. This is particularly so when blows occur, as they are prone to do, around the surfaces of the electrodes nearest to the central axis of the furnace. When it is necessary to "slip" an electrode, i. e., to lower it in its holder, or to make repairs on the equipment above

the furnace proper, it even becomes necessary for the workmen to stand upon a sheet of corrugated iron laid over the charge, under conditions which even the hardest men can withstand for only a few minutes at a time.

Furnace equipment suitable for withstanding the conditions prevailing, and satisfactory from the standpoint of electrical efficiency, represents a very large item of expense in the manufacture of ferro-alloys, and at the best it is always difficult to get parts which will live under the severe operating conditions and to repair and replace them, or to slip or replace electrodes during operation. It will be understood, of course, that the operation is a continuous one from the time that a furnace is put on heat until it is shut down for rebuilding.

My invention greatly improves the manufacturing process and minimizes the difficulties above briefly outlined. It makes possible the use of automatic charging machines, which to date have never been found satisfactory for this use, vastly improves the working conditions and increases the over-all efficiency of the smelting operation.

In the accompanying drawings, illustrating present preferred embodiments of the invention, Fig. 1 is a vertical section through a ferro-alloy furnace employing horizontal electrodes, and Fig. 2 is a similar view showing a furnace with electrodes arranged at an angle. In each case the electrodes extend laterally into the furnace chamber and terminate at a substantially common level therein.

Referring first to Fig. 1, there is shown a furnace having a shell 2 and a refractory body or lining 3 providing a furnace chamber 4. The furnace is of the open-topped crucible type and is provided with three equiangularly spaced horizontal electrodes 5. The electrodes project through openings 6 in the furnace wall. A refractory ring 7 backed by a cooler 8 is provided in the annular space around the electrode. Each electrode is secured to a pad 9 by a clamp 10. The pads 9 carry rollers 11 operating on fixed ways 12, so that the electrodes may be adjusted inwardly or outwardly. The clamps 10 are connected to the current supply, as indicated at 13, and as the electrodes are consumed, the clamps may be loosened and re-positioned thereon.

The charge material is supplied to the top of the chamber in a loose pervious condition, preferably as a loose pervious admixture of small particles of the constituent materials, although it may be desired in some cases to agglomerate the materials into larger pieces. In the manufacture of ferro-silicon, the charge will consist of silica, iron oxide or scrap and coke or other carbonaceous reducing material. For the purposes of this specification, I designate iron oxide or iron ore, and metallic iron as "iron-source material." A charging platform 14, level with the top of the furnace, is provided and, if desired, the charge may be shoveled in manually as in present practice. In operation the furnace will be kept substantially filled with charge material, as indicated in Fig. 1. It will be noted that the charge material thus forms a deep layer over the electrodes, completely covering those parts of the electrodes lying within the furnace chamber and extending uninterruptedly over the area of the furnace chamber.

The heating of the charge in a ferro-alloy furnace is rather markedly localized, differing in this respect, among others, from iron or steel making operations. In the ordinary ferro-alloy

process now in use, it is difficult, if not impossible, to control the location and size of the reaction zone with the desired degree of precision, and the result is that the efficiency of the operation is frequently reduced and current and electrode costs are higher than they should be. This is due in part to the fact that the path of the current cannot always be directed or confined to the same location, as a portion of the current may

flow from the vertical circumference of one electrode to another electrode and from electrodes to the bottom of the furnace or even around the furnace walls. In the process now being described in connection with Fig. 1 of the drawings, the reaction zone is closely confined to the central portion of the furnace between the upper and lower planes of the electrodes with the result that maximum furnace efficiency and minimum current and electrode costs result. In this process the path of the current can be more definitely controlled and the greater part of the current will flow from the end of one electrode to the end of the other electrodes, thus localizing the reaction zone.

25 The passage of the electric current through the charge raises the charge in the heating zone to reaction temperature, whereby the ferro-alloy is formed. It descends by gravity to the bottom of the furnace and is periodically drawn off through a pouring spout 15 in known manner. As the charge material is consumed by the reaction, the overlying mass which overlies the reaction zone slowly descends and fresh charge material is supplied at the top as the operation proceeds.

30 During the formation of the ferro-alloy gases are evolved and these pass upwardly through the loose bed of charge material overlying the reaction zone. Since this bed is in the nature of a continuous and uninterrupted mass of loose particles, the tendency of the gases to channel through the charge material, with resulting blows, is minimized. The process differs markedly in this respect from the ordinary process wherein the electrodes extend vertically upward through the descending mass of charge material providing paths of minimum resistance for the evolved gases. In my process the charge material tends to descend more uniformly, thus improving the operation of the furnace, and since there are no electrodes projecting out of the zone of moving charge material the work of charging is much less arduous and the need for raking and otherwise locally placing the charge material is minimized.

35 The reasonably uniform flow of hot gases upwardly through the charge material overlying the reaction zone preheats it in a more nearly uniform manner than heretofore, thus tending further to improve the operation of the furnace. 40 If desired, the furnace may be provided with an adjustable hood 16 leading to a flue 17 whereby the sensible heat of the gases may be utilized or the dust and gases carried off or utilized.

45 Fig. 2 shows the practice of the invention in a furnace having inclined electrodes 20 which extend laterally through the sides of the furnace into the furnace chamber and terminate at a substantially common level therein. While theoretically less efficient than the horizontal electrode arrangement of Fig. 1, the arrangement shown in Fig. 2 is nevertheless highly efficient and has the advantage that the breaking load on the electrodes is reduced.

50 In Fig. 2 I have shown a mechanical charger or stocker 21. It is feasible in my invention to

use mechanical chargers whereas practical experience shows that they are impractical in present-day operations.

In order to have a full understanding of my invention, it is important to differentiate between material which is substantially static in the furnace and material which moves downwardly in appreciable amount as the process goes on. Early in the operation of the process, a mass of fused or partially fused charge material will form around and below the reaction zone and, having formed, will be substantially static, i. e., it will move but little, if at all, in the subsequent operation of the furnace. This mass is more or less honeycombed and does not prevent drawing off of the formed ferro-alloy. It aids in concentrating the working of the furnace at the central portion. I have already mentioned that in the ordinary ferro-alloy process now in use the location and size of the reaction zone may change considerably, with adverse effects upon the overall operation, but, in any case, the furnace material lying within the vertical projection of the confines of the reaction zone is particularly notable for downward movement of the charge material and upward flow of a large quantity of evolved gases. In the present-day process the electrodes extend upwardly through this zone, with the adverse consequences hereinabove stated. It should therefore be recognized that while, in the practice of my invention, the configuration of the furnace and the positioning of the electrodes may be varied, even to the extent, in the case of a very wide furnace, of having the electrodes not penetrate through the furnace wall, it is vital that conditions be so maintained that there is no substantial material movement of the charge material and no egress of substantial quantities of evolved gases in the zones where the electrodes extend out of the charge material.

Many of the advantages of my invention have been indicated in the foregoing description. To them may be added the following: All electrical contacts between the pads and holders and between the pads and electrodes can be kept clean and away from the heat of the furnace (which heat is variable in present-day furnaces), and consequently a more uniform and improved electrical circuit is obtainable. Less sensible heat is lost because blows are minimized and, in any case, material heat conservation is made possible by taking off the hot gases and using them for preheating the charge or in waste heat boilers, or otherwise. In present-day operations a large amount of material is entrained by the rising gases as dust and is lost, in addition to which the dust may blight the territory adjacent the plant. The costly and intricate water-cooling systems are eliminated, greater continuity of furnace operation and greater efficiency are obtained and the working conditions of the operators are vastly improved.

I have illustrated and described two present preferred embodiments of the invention. It will be understood, however, that these are by way of illustration only and that the invention may be otherwise embodied or practiced within the scope of the following claims:

I claim:

1. The process of making ferro-alloys of iron and an alloying metal in an electric furnace having a chamber and electrodes extending laterally into the chamber and terminating at a substan-

tially common level therein, which comprises making up a charge in loose pervious condition and consisting of the constituent materials in admixture, charging the furnace therewith, initially raising a portion of the charge to reaction temperature and thereafter providing substantially the entire heating energy for the process by supplying electric current to said laterally extending electrodes and passing said electric current through the furnace charge, maintaining the reaction zone localized in and around the inner ends of the electrodes whereby the ferro-alloy is formed in a localized zone and gases are evolved, but without substantial volatilization of the alloying metal, drawing off the ferro-alloy in molten state from the bottom of the furnace chamber without supplying any substantial amount of heat thereto from any other source, passing the evolved gases upwardly through the overlying charge material, supplying fresh charge material above the level of the reaction zone as the operation proceeds and at all times maintaining a layer of charge material in the furnace above the reaction zone, which layer completely covers those parts of the electrodes lying within the vertical confines of the reaction zone and extends uninterruptedly over the area defined by the vertical projection of those confines.

2. The process of making ferro-silicon in an electric furnace having a chamber and electrodes extending laterally into the chamber and terminating at a substantially common level therein, which comprises making up a charge in loose pervious condition from silica, carbonaceous and iron-source material in admixture, charging the furnace therewith, initially raising a portion of the charge to reaction temperature and thereafter providing substantially the entire heating energy for the process by supplying electric current to said laterally extending electrodes and passing said electric current through the furnace charge, maintaining the reaction zone localized in and around the inner ends of the electrodes whereby the ferro-silicon is formed and gases are evolved, but without substantial volatilization of silicon, drawing off the ferro-silicon in molten state from the bottom of the furnace chamber without supplying any substantial amount of heat thereto from any other source, passing the evolved gases upwardly through the overlying charge material, supplying fresh charge material above the level of the reaction zone as the operation proceeds and at all times maintaining a layer of charge material in the furnace above the reaction zone, which layer completely covers those parts of the electrodes lying within the vertical confines of the reaction zone and extends uninterruptedly over the area defined by the vertical projection of those confines.
